United States Patent Office.

D. M. THOMAS, OF DOWAGIAC, MICHIGAN.

Letters Patent No. 61,775, dated February 5, 1867.

IMPROVED BED BOTTOM.

The Schedule referred to in these Letters Patent and making part of the same.

TO ALL WHOM IT MAY CONCERN:

Be it known that I, D. M. THOMAS, of Dowagiac, Cass county, State of Michigan, have invented a new and improved Spring Bed Bottom; and I do hereby declare that the following is a full, clear, and exact description thereof, reference being had to the accompanying drawings, making a part of this specification, in which—

Figure 1 is a longitudinal section, taken vertically through the improved bed bottom.

Figure 2 is a top view of the bed bottom.

Figure 3 is a bottom view.

Similar letters of reference indicate corresponding parts in the several figures.

This invention consists in constructing a bed bottom of narrow spring strips arranged side by side in parallel rows, and secured in inclined planes, crossing each other in such manner that the weight to be sustained will be received upon the upper ends and inclined surfaces of said springs, and a very comfortable and elastic support will be afforded, as will be hereinafter described.

To enable others skilled in the art to understand my invention, I will describe its construction and operation.

In the accompanying drawings, A A represent two longitudinal bars which are secured together parallel to each other, and at a suitable distance apart, by means of cross-bars B B, thus forming a frame for sustaining the springs and keeping them in place. The cross-bars B B are secured to bars A A, in pairs, as shown in the two figures, 2 and 3, and each pair is adapted for sustaining two rows of springs. Said bars are notched on their upper and lower corners for the purpose of receiving narrow springs C C and affording lateral support for keeping these springs in their proper places. The spring C may be made of wood or of metal or other suitable substance, and those portions which extend above the bars B may be reduced in thickness so as to give them the proper degree of elasticity. The but ends of these springs are secured firmly to the bottom sides of the bar B, and extend upward in inclined planes so as to lie in notches which are made in the upper sides of the bars B. The springs are arranged side by side at suitable distances apart, and those springs which are secured to the bottom of one bar lie upon and are supported by the bar lying nearest to it. By this arrangement the springs are inclined in opposite directions, and each spring is sustained at two points by each pair of bars B. To prevent the upper ends of the springs from rising above their natural plane they are connected together by cords a a, as shown in figs. 1 and 2.

I do not confine my invention to any definite number of springs, as the number will be increased or diminished according to circumstances. Nor do I confine my invention to the above-described arrangement of springs for a bed bottom, as such arrangement may be adopted for seats, sofas, and for other purposes.

I am aware that bed bottoms have been constructed of inclined springs, secured at the ends of a frame, and having strips attached to their ends, but these I do not claim as my invention. It will be seen that I have an arrangement of inclined springs by which straight strips are dispensed with and the entire supporting surface made up of springs.

Having described my invention, what I claim as new, and desire to secure by Letters Patent, is—

A spring seat or bed bottom which is composed of inclined springs that are supported and held in place by means of transverse bars B, substantially as I have herein described.

D. M. THOMAS.
